INDOOR PORTABLE PRACTICE PUTTING GREEN

Filed Dec. 19, 1927

UNITED STATES PATENT OFFICE

HERBERT R. BUSSE, OF SEATTLE, WASHINGTON

INDOOR PORTABLE PRACTICE PUTTING GREEN

Application filed December 19, 1927. Serial No. 241,005.

My invention relates to an improvement in practice putting greens, especially that type which is intended to be used in the home, and which must, therefore, be cheap and easily

5 portable.

One object of my invention is to make a green of the general class described above, which is so constructed as to improve the touch of the player, as well as his accuracy, 10 for in stroking a ball on a natural green, the success of the putt is as often dependent upon the use of the correct amount of force, as in the accuracy of direction.

A further object is the provision of such a 15 practice green wherein the balls, whether they attain the objective—dropping into the cup—or whether they miss the cup, will be returned to the player, or in his direction. A further object is the construction of such a 20 practice putting green, which, in addition to being portable, is cheaply yet strongly constructed so that it may be sold at a low cost, and thus be within the reach of every player.

A further object is the provision of means 25 whereby such a portable practice green, though of relatively light construction, will not be displaced by the striking of the ball, but will hold fast and thus assure to the player that his shot will not be spoiled by

30 the movement of the green.

A further object is the provision of a plurality of apertures or holes in such a green, with provision for covering as many as may be desired so that the surface is smooth and 35 flush and presents no obstruction to balls which may pass thereover on their way to another hole. This is a provision intended both to obviate too much wear on one hole and on the covering leading thereto, and to

40 provide variety for the player.

A further object in indoor putting greens is the provision of means whereby a rim shot will be simulated much as occurs when a 45 player puts his ball on the outdoor green so that it just strikes the rim of the cup and rolls around the rim without dropping therein. So, by providing a contour of the hole in the practice green, in a peculiar manner, the ball may be caused to run around the rim, but not drop thereinto.

Other objects may be ascertained from a study of the following specification, the drawings forming a part thereof, and the claims terminating the same.

In the accompanying drawings, my invention is shown in a form which is now preferred by me.

My invention comprises the novel parts and the novel combination and arrangement thereof as shown in the accompanying drawings, described in the specification and particularly defined by the claims.

Figure 1 is a plan view of my green.

Figure 2 is a section on line 2—2 of Figure 1.

Figure 3 is a section on line 3—3 of Figure 2.

Figure 4 is a detail section through one of the holes and its cover.

Figure 5 is a section similar to Figure 4, showing a slight modification.

While it will be apparent that such a practice green might be constructed of various materials and in various forms and shapes, I prefer that it be constructed of sheet metal 75 for cheapness and convenience of manufacture, and to give it lightness for ready portability. Thus, the sheet 1 comprises the surface of the green, except as it may be covered by a strip of felt 2 or like material, simulating grass and tending to prevent noise and retard the ball much as does the grass of a putting green. This sheet 1 may be formed in a generally triangular shape and is apertured as indicated at 10 and 11, 80 the apertures being of a size to permit passage of a golf ball of the standard size, as is indicated at B. To prevent the balls which are stroked upon the surface 1 from overshooting the mark and dropping upon the floor beyond, I provide a barrier or guard at the rear side, at least, of the surface 1, and preferably this extends about both sides and the rear edge of the surface, as indicated at 85 12. These flanges may very conveniently and cheaply be formed by flanging upwardly and inwardly the edges of the metal sheet 1. They should extend to a height approximately half the height of a golf ball so that if a ball strikes them, it will strike at about

90 95 100

its center of gravity, and as the flanges are resilient, the ball will rebound therefrom and be started on its return to the player.

It will be understood that the surface 1 is somewhat inclined. That portion which is toward the player, and which I designate the forward portion, preferably is somewhat more sharply inclined than the rear portion, there being a rolling break at 13. The rear portion, however, is inclined in the same general direction as the forward portion.

One object of the break at 13, and the difference in inclination, is to permit the player to practice in the attainment of the proper touch. The hole 10 is placed in the rear portion of the surface 1, beyond the break 13. Thus, a player must stroke his ball so that it will just rise past the incline 13 or it will fail to stop and drop in the hole 10, but will 20 jump past this, if stroked too hard. The apertures 11, however, are placed in the forward portion so that a ball may be putted up the inclined forward portion and drop directly into one of these apertures, if the same 25 is uncovered.

This, then, serves chiefly as a means to improve accuracy, while the aperture 10 requires both accuracy and the proper touch in order to hole the ball.

30 I provide covers 3 which are covered with material 32 similar to the cover 2 for the surface 1, these covers 3 being of a size to fit within the apertures 10 or 11 and fill them, and thus these covers with their covering

35 material 32 come flush with the putting surface and offer no obstruction thereto when in place. As many holes as may be desired may be thus covered, and the hole in use may be changed from time to time for variety

40 and to prevent undue wear on the cover 2 surrounding any one hole. The means for supporting these covers 3 will be described hereafter, but it should be noted that they are supported from below and have a weight as 45 31 to hold them in place and prevent their displacement when a ball rolls thereover. Also, a notch as indicated at 30 may be provided in one edge for engagement by a finger or thumb to remove the covers when desired.

50 To enable a ball putted from a carpet, at a distance from the green, to rise onto the inclined green without undue shock and without disturbing its direction when it starts up the incline, I may provide a forwardly projecting flange 14 at the forward edge of the surface 1, the forward edge of this flange 14 being in contact with the floor and substantially parallel therewith, and

55 changing direction gradually until it merges into the inclined surface of the green. The cover 2 may similarly be extended forward as indicated at 20, and may project slightly beyond the forward edge of the flange 14 to 60 soften the rise of the ball over the edge of

this flange and to overlie the edge of adjacent carpet, if this be found desirable.

Any convenient support may be provided for the green thus described and I have shown a simple angular sheet metal leg 4 secured beneath the sheet. This leg is not shown as secured directly to the sheet 1, though it might be so secured, but I have shown it as secured to a cup 5 which is directly secured beneath the sheet 1 in such a position as to receive balls which pass thru any of the apertures 10 or 11. The bottom of this cup 5, which may be made of sheet metal for lightness and cheapness, is inclined in all directions toward an aperture 50 in one side which is large enough to permit passage of a ball, as indicated in dotted lines in Figure 2. A return trough or chute 6 connects with this aperture 50 and is directed forwardly therefrom, and is somewhat inclined 70 forwardly, so that any ball which drops through one of the apertures in the green will be directed by the inclined bottom surfaces of the cup 5 toward the aperture 50 and will then be directed forwardly by the inclined chute 6 so as to be returned towards the player. The green itself is so inclined and so guarded by the flanges 12 that any ball which does not drop through one of the apertures will be returned in the direction from 75 which it came. Hence, the player will not have to go to the green or beyond it to retrieve balls, but they will always be returned in his direction.

To further assist in accuracy and to prevent displacement of the green, I may provide a weight 7 at the forward edge of the green which serves to steady the entire green when struck by a ball.

To simulate rim shots such as occur in outdoor greens and putting cups, and which are due to the somewhat rounded contour of the edge of the cup, I may provide rings 8 which are formed by rolling the edges of the apertures, as in Figure 5, or which are formed as 100 separate rings, secured beneath each of the apertures 10 or 11, as shown in Figures 2, 3, and 4, and of somewhat smaller internal diameter than these apertures, but yet large enough to permit a ball to pass therethrough. The rolled edge of the apertures, or the upper inner surface of these rings, is rounded as 105 indicated at 80.

The ball striking this rounded surface will not immediately drop therethrough, if it has any velocity at all, but will run around, and by its centrifugal force thus developed will be thrown out of the aperture rather than be permitted to drop through it. To further simulate the conditions in an outdoor green, these rings, at least the visible portions thereof, may be painted brown to simulate the space between the upper edge of the metal cup and the surface of the earth. These rings 8, or their counterparts, the 110

115 120 125 130

rolled edges shown in Figure 5, lie beneath and support the covers 3. To prevent displacement of a cover from the support shown in Figure 5, wherein the cover may tend to slide on the rounded surface 80, I may provide a tab 38 on the cover, fitting within a depression or groove 83 in the curled edge 8.

5 What I claim as my invention is:

1. A portable practice green comprising a sheet defining an apertured surface inclined upwardly and rearwardly from a forward floor-engaging edge, said forward edge being weighted to prevent displacement when struck by a ball.
- 10 2. A portable practice green comprising a sheet defining a surface having a plurality of apertures, and inclined upwardly and rearwardly from a forward floor-engaging edge, a ball-receiving cup secured beneath the several apertures, and an inclined, forwardly directed return chute leading therefrom, said cup being inclined towards said chute.
- 15 3. In a practice green, a sheet defining a playing surface, and apertured to permit passage of a ball, the material forming the periphery of the aperture being rounded downwardly from the general plane of the playing surface, and a disk adapted to rest upon the rounded periphery of the aperture to close the same, and to come flush with the playing surface.
- 20 4. A practice green as in claim 3, the disk being of sheet metal, and a weight secured to its under side to prevent its accidental displacement.

25 Signed at Seattle, King County, Washington, this 12th day of December, 1927.

30 HERBERT R. BUSSE.
